DESIGN FOR A DISPLAY STAND

Max L. Ferentz, New York, N. Y.; Laura Ferentz,
New York, N. Y., administratrix of said Max
L. Ferentz, deceased

Application February 17, 1934, Serial No. 50,758

Term of patent 3½ years

To all whom it may concern:

Be it known that I, Max L. Ferentz, a citizen of the United States, and resident of New York city, in the county and State of New York, have invented a new, original, and ornamental Design for a Display Stand, of which the following is a specification, reference being had to the accompanying drawing, forming part thereof.

Fig. 4 is a side elevational view of the pedestal only of the display stand of Fig. 1.

I claim:

The ornamental design for a display stand substantially as shown and described.

MAX L. FERENTZ.
